UNITED STATES PATENT OFFICE.

MEYER LIEBMAN, OF NEW YORK, N. Y.

PRINTING DEVICE.

1,112,629.

Specification of Letters Patent. Patented Oct. 6, 1914.

Application filed March 14, 1914. Serial No. 824,800.

To all whom it may concern:

Be it known that I, MEYER LIEBMAN, a citizen of the United States, and resident of New York, in the county of Bronx and State of New York, have invented certain new and useful Improvements in Printing Devices, of which the following is a specification.

My invention relates to printing devices 10 and more particularly to a hand operated device for printing characters of any preferred design on tickets, cards, papers, and other articles.

It is one of the objects of my invention to, 15 provide a simple and convenient device whereby the character or letter is inked after each movement of the same to the printing position, and whereby the member carrying the character presents the character to the 20 inking means when the printing device is in its normal or open position.

Another object of the invention is to provide a bodily movable inking means arranged so that the same will not be in the 25 path of the member carrying the character, but may be automatically forced into contact therewith after the character carrying member is in inking position.

Another object of the invention is to 30 provide a novel removable and renewable inking device for the mechanism.

Still another object of the invention is to completely inclose the inking pad and to retain the character and pad in a casing 35 while the device is not in use.

The above and other objects and the novel features of the invention will be apparent from the following description, taken in connection with the drawings, in which—

40 Figure 1 is a side elevation of the device embodying my invention, part thereof being shown in section, the device being shown in normal or open position; Fig. 2 is a side elevation of the device shown in Fig. 1, and 45 showing the same in closed position; Fig. 3 is a plan view of the upper jaw of the device with the cover thereof open; Fig. 4 is a cross sectional view of the inking device; and Fig. 5 is a side elevation partly in section showing a modified form of my invention.

Referring to the drawings, 10 and 11 respectively designate the upper and lower handle levers forming the grip of the device 50 and having the studs 12 and 13 on their inner

sides to center and hold in position a spring 14 which normally holds the levers apart. The levers 10 and 11 are pivoted together at the pivot screw 15 and beyond the said screw they carry the jaws 16 and 17 respectively. 60

The lower jaw 16 connected to the upper lever 10 carries a plate 18 which has an upwardly extending arm 19 projecting through the opening 20 at the rear end of the lower wall 21 of the casing 22 constituting the upper jaw. The plate 18 is secured to the jaw 16 by means of screws 23. The lower jaw 16 constitutes the support or platen for the sheet receiving the impression and also 70 carries a guide plate 24 which is bifurcated at its outer end and secured to the lower jaw by means of the screw 25. The bifurcated end 26 of the plate is bent upwardly as at 27 and the plate is spaced throughout most 75 of its length from the said jaw to provide a space 28 to receive the card, ticket or other article to be printed.

The casing comprising the jaw carried by the lever 11 has a cylinder or roller 29 carried by the pivot 30 at the forward end thereof and carries a letter or character 31 of any suitable design on its outer peripheral face. The face of the cylinder can of course be made wide enough for a complete word or some other character requiring a wide face. The cylinder 29 is pivoted so as to project from the casing 22 through the opening 32 at the forward end of the casing and when the cylinder is rotated to a printing position the character 31 also projects through said opening 32 and extends between the bifurcations at the end 26 and is pressed onto the sheet 8 inserted in the space 28 between the jaw 16 and guide plate 24. 85 90 95

I have provided a mechanism for rotating the cylinder one quarter of a revolution each time the levers 10 and 11 are closed and each time they are opened, when closing the levers the cylinder 29 is rotated so as to print the character on a sheet inserted in the space 28 and when the levers 10 and 11 are released the cylinder is rotated back a quarter of a revolution to its original and inking position where it is retained when the device is not in use. The mechanism for rotating the cylinder comprises a Y-shaped slot in the face of the cylinder, the shank portion 33 being radially arranged and near the center or pivot of the cylinder, and the two branches 100 105 110

34 and 35 extend outwardly from the portion 33 toward the periphery of the cylinder. A lever 36 is pivoted at 37 in one side of the casing 22 and at its outer end has a pin 38 which fits in the Y-shaped slot and when the lever is oscillated the said pin 38 moves in the Y-shaped slot and serves to rotate the cylinder 29 a quarter of a revolution. The branches 33, 34 and 35 are cut curved about 5 the pivot 37 as a center so that the pin 38 which moves about the center 37 will readily pass along the said branches of the Y-shaped slot. The inner end of the lever 36 is bifurcated to provide a slot 39 to receive a stud 10 40 projecting laterally from the arm 19 attached to the plate 18 on the jaw 16. As the lower jaw is raised by the lever 10 or as the device is closed the stud 40 will move in the slot 39 and rock the lever 36 on its pivot 37 15 to rotate the cylinder 29. When the jaws are opened by the spring 14 the lever 36 will be rocked back to its original position and also return the cylinder 29 to the position shown in Fig. 1.

20 25 The inking means comprises the hollow metal casing shown in Fig. 4 consisting of a rectangular part 41 and a rectangular part 42 of smaller dimension joined by the shoulder 43. The larger hollow rectangular portion 41 contains a pad 44 of suitable fabric or other material which is porous. The material 44 rests on the shoulder 43 and is retained in the cavity 41 by the inner flange 45. The cavity in the part 42 of the inking device opens into the cavity 41 and is adapted 30 to contain ink 46 which saturates the material 44 constituting the pad. The rear end of the cavity 42 is closed by a hollow knurled screw 47 which fits into the cavity 42. The top of the casing has an opening 48 therein which is closed by a laterally movable cover 49 pivoted at 50 on the rear wall 51 of the casing. The cover has an angular edge 491 which engages the edge 492 and 35 edge 491 which engages the edge 492 and limits the movement of the cover. The inking device shown in Fig. 4 is passed into the casing through the said opening 48 and rests on the bottom wall 21 and is bodily movable longitudinally of the casing.

40 45 50 A pin 52 passes through the opening 53 in the rear wall 51 of the casing and the inner end thereof is adapted to engage the rear end or cover screw 47 of the inking pad. The outer end of the pin 52 has a head 54 which limits its movement inwardly, the said head being engaged by a shoulder 55 on the lever 10 which pushes the pin inwardly when the lever 10 is released. This inward movement of the pin 52 by the lever 10 causes the inking pad to be moved forwardly bodily into contact with the letter or character 31 on the printing cylinder 27 to ink the same. When the handle levers 10 and 11 are pressed together, the pin 52 is released and the simultaneous rotation of the cylinder 29 and

the character 31 thereon pushes the inking pad rearwardly a slight distance and there is therefore no rubbing action between the pad and the character either when the character leaves the pad or when the pad is moved into contact with the character by the pin 52. This arrangement provides for an even distribution of ink on the character and prevents any friction of the parts on one another.

70 75 In Fig. 5, I have shown a slightly different form of device embodying my invention, wherein the impression cylinder 29 has a boss 55 provided with a series of teeth 56 engageable by the teeth 57 on an arm 58 carried by a plate 59 secured to the lower jaw 16 by screws 60. It will be clear that when the handle levers 10 and 11 are released and spring apart, the teeth 57 will engage the teeth 56 and rotate the cylinder 29 so 80 that the character 31 thereon will move to a position opposite the inking pad 44. When the jaws are closed together the teeth 57 will engage the teeth 56 and move the cylinder into the position shown in Fig. 5 so that 85 the character 31 will project through the bifurcation in the plate 24 into the space 28 where the sheet to be printed is located. The printing pad and other arrangements in this device are substantially the same as 90 those heretofore described with the exception that the printing pad is mounted on an angular plate 61 secured on the interior of and to the side wall of the casing 22 and provided with a shoulder 62 which serves to 95 limit the rearward movement of the printing pad.

100 105 The operation of the device will be apparent from the foregoing description. It will be clear that I have provided a simple and convenient printing device which may be manipulated by one hand. The device consists of but few parts and will therefore be inexpensive to manufacture. The inking pad is removable and is mounted so that it will not be presented to ink the type on the impression member until after said type reaches the inking position.

110 115 While I have shown and described my invention in detail, I do not wish to be limited to the exact construction herein shown.

Having thus described the invention, what I claim is:

1. In a printing device, the combination of a pair of pivotally connected jaws, one of said jaws having a handle, an impression member pivoted on one of said jaws, inking means for said member, and means operated by the opening movement of said jaws for moving said member to its inking position and applying the inking means thereto after said member reaches the inking position.

2. In a printing device, the combination of two pivotally connected elements, the free ends of which tend to remain spaced

- apart, an impression member carried by one of said elements, inking means for said member, and means for moving said impression member to its inking position and there-
 5 after presenting the inking means to said member, said moving means being actuated by one of the pivotally connected elements.
3. In a printing device, the combination of two pivotally connected elements, an impression member and inking means therefor carried by one of said elements, a casing inclosing said impression member and inking means, and actuating means for said impression member and inking means, said actuating means extending into said casing and being operated by the other of said elements, and handles for operating said elements.
4. In a printing device, the combination of two pivotally connected jaws terminating in handles, one of said jaws comprising a casing having an opening therein and the other jaw comprising a support for the sheet which receives the impression, an impression member pivoted within said casing, and means for operating said member to project the printing portion thereof through said opening into contact with a sheet on said support.
5. In a printing device, the combination of two pivotally connected jaws terminating in handles, one of said jaws comprising a casing having an opening therein, an inking means in said casing, an impression member pivoted in said casing and normally in contact with said inking means, means for operating said impression member to move the same to its printing position and back into contact with said inking means, and an element projecting into said casing and engageable by one of said handles to operate said inking means.
6. In a printing device, the combination of two pivotally connected jaws, one of said jaws having a casing movable therewith and provided with an opening therein and the other jaw comprising a support for the member which receives the impression, an impression member and inking means therefor located within said casing, means for actuating the impression member to project the printing portion thereof through said opening in the casing and for returning the same to inking position, and means for presenting said inking means to the impression member.
7. In a printing device, the combination of two pivotally connected jaws, one of said jaws constituting a casing and the other jaw comprising a support for the sheet which receives the impression, an impression member pivoted in said casing, a removable inking device in said casing, means for operating the impression member to move the same to its printing position and back to its inking position, and means for presenting the inking device to the impression member after the latter reaches its inking position.
8. In a printing device, the combination of two pivotally connected jaws terminating in handles, one of said jaws comprising a casing and the other jaw comprising a support for the sheet which receives the impression, an impression roller pivoted in said casing adapted to turn on its pivot to inking and impressing positions, an inking device therefor movable in said casing, an element carried by said supporting jaw and extending into said casing and connected to operate said roller, and means whereby the inking device is presented to the impression roller when the latter is moved to its inking position.
9. In a printing device, the combination of two pivotally connected jaws terminating in handles, one of said jaws comprising a casing and the other jaw comprising a support for the sheet which receives the impression, an impression roller pivoted in said casing, an inking pad therefor bodily movable in said casing, an element carried by said supporting jaw and extending into said casing and connected to operate said roller on its pivot, and means whereby the inking pad is presented to the impression roller when the latter is moved to its inking position, said means comprising a pin extending into the casing, said pin being engageable by one of said handles when the jaws are completely opened and after the roller is in its inking position.
10. In a hand printing device the combination of two levers having a pivotal connection therebetween intermediate their ends, said levers terminating in handles forming a hand grip on one side of said pivotal connection and having jaws on the opposite side of the pivotal connection, one of said jaws constituting the support for the article to be printed, an impression member mounted on the other jaw and movable to and from an inking position, means for moving said impression member into engagement with the article to be printed, an inking device, and means for operating said inking device to move it into engagement with the impression member after the latter reaches the inking position.
11. In a hand printing device the combination of two levers having a pivotal connection therebetween, said levers terminating in handles forming a hand grip on one side of said pivotal connection and having jaws on the opposite side of the pivotal connection, one of said jaws constituting the support for the article to be printed, an impression member pivoted on the other jaw, means for rotating said impression member on its pivot and into engagement with the article to be printed, an inking device mounted on the jaw with the impres-

sion member and movable therewith, and means for actuating the inking device to positively move it into engagement with the impression member when the jaws are opened.

12. In a printing device, the combination of a casing having openings therein, an impression member pivoted in the casing, an inking means for said member, said inking means being removable through one of said openings in the casing, means for operating said impression member to project the printing portion thereof through one of said openings, and means for presenting said inking means to the impression member after the latter reaches its inking position.

13. In a hand printing device the combination of two levers having a pivotal connection therebetween, said levers terminating in handles forming a hand grip on one side of said pivotal connection and having jaws on the opposite side of the pivotal connection, one of said jaws constituting the support for the article to be printed, an impression member mounted on the other jaw, means connected to the article-supporting jaw capable of moving the impression member to printing position when the jaws are closed together, an inking device on the jaw with the impression member, and a device for moving the inking device toward

and into contact with the impression member when said jaws swing apart.

14. In a hand printing device the combination of two levers pivotally connected together intermediate their ends, said levers terminating in handles forming a hand grip on one side of said pivotal connection and having jaws on the opposite side of the pivotal connection, one of said jaws constituting a support for the article to be printed, the other jaw comprising a casing, an impression member pivoted in said casing and adapted to turn on its pivot to inking and impressing positions, a type on said member, an inking device mounted in said casing, means whereby said inking device is moved against said type when the jaws swing apart and after the type reaches the inking position, and an arm on the supporting jaw and extending into said casing, said arm being adapted to cause the type on said member to move from printing to inking position or vice versa as the jaws are opened or closed, respectively.

In testimony whereof I affix my signature in presence of two witnesses.

MEYER LIEBMAN.
